(57) **CLAIM**

The ornamental design for an autonomous vehicle roof housing, as shown and described.

DESCRIPTION

The present application is related to application Ser. No. 29/491,722, entitled Autonomous Vehicle Overall Exterior; to application Ser. No. 29/491,717, entitled Tire Rim; to application Ser. No. **29/491,734**, entitled Autonomous Vehicle Headlamp; to application Ser. No. 29/491,730, entitled Autonomous Vehicle Taillamp; to application Ser. No. 29/491,726, entitled Autonomous Vehicle Wing Assembly; and to application Ser. No. 29/491,727, entitled Autonomous Vehicle Rear Vent/Reflector, the entire disclosures of which are incorporated by reference herein.

FIG. 1 is a front perspective view of an autonomous vehicle roof housing according to a first embodiment of our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an autonomous vehicle roof housing according to a second embodiment of our design;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top elevation view thereof; and,

FIG. 14 is a bottom elevation view thereof.

Broken lines are environmental only and form no part of the claimed design.

1 Claim, 14 Drawing Sheets

Related U.S. Application Data

division of application No. 29/514,665, filed on Jan. 15, 2015, now Pat. No. Des. 758,269, which is a division of application No. 29/491,723, filed on May 23, 2014, now Pat. No. Des. 731,383.
